UNITED STATES PATENT OFFICE.

WILLIAM J. GAGNON, OF BRIDGEPORT, CONNECTICUT, ASSIGNOR TO THE BEAD CHAIN MANUFACTURING COMPANY, OF BRIDGEPORT, CONNECTICUT, A CORPORATION OF CONNECTICUT.

DESIGN FOR A PULL-CHAIN PENDANT.

Application filed May 25, 1926. Serial No. 17,853. Term of patent 14 years.

To all whom it may concern:

Be it known that I, WILLIAM J. GAGNON, a citizen of the United States of America, residing at Bridgeport, in the county of Fairfield, State of Connecticut, have invented a new, original, and ornamental Design for a Pull-Chain Pendant, of which the following is a specification, reference being had to the accompanying drawings, forming part thereof.

Figure 1 is a perspective view of a pull

chain having a pendant showing my new design.

Figure 2 is another perspective view from a different angle.

I claim:

The ornamental design for a pull chain pendant as shown.

In testimony whereof I have signed my name to this specification.

WILLIAM J. GAGNON.
